INDICATING INSTRUMENT

Elsie G. Fulboam, Andover, N. J.

Application August 17, 1946, Serial No. 691,223

2 Claims. (Cl. 235—125)

1

This invention is an improved marking and indicating device or instrument designed mainly for use in scoring test and examination papers in schools and other educational institutions; and comprising means for collecting and indicating all the necessary standard data which the test or examination is planned to reveal.

An important object of the invention is to provide a marking and indicating device containing strips of tape or film or the like, each bearing selected data on the face thereof and capable of being actuated to move the desired indication into view, so that the final result can be read at once when the marking is finished.

A further object of the invention is to provide a marking and indicating device in which the mode and rate of actuation of the strips can be adjusted when a change is necessary; and which also embodies suitable means for reverse movement or back-spacing and connections for enabling all of the strips or the like which carry the data to be returned to starting position in readiness for further use when the process of marking any individual paper is completed.

More specifically an object of the invention is to provide a device that makes a mark and simultaneously records the addition or deduction of one or more units.

Another object of the invention is to provide a marking and indicating device which is electrically controlled and operated and which is very simple, inexpensive and efficient in construction and operation.

The nature and advantages of the invention are set forth in the following description, and the novel features are pointed out in the appended claims. This disclosure, however, is explanatory only and many changes may be made in practice without departing from the essential structure in which the invention resides.

On the drawings:

Fig. 1 is a perspective view of the outside casing of a marking and indicating device or instrument according to this invention.

Fig. 2 is a sectional view of the marking member.

Fig. 3 shows in top plan the operating mechanism within the casing.

Fig. 4 is a side view enlarged of the principal operating members for imparting motion to the strips.

Fig. 5 is a similar view of the mechanism for back-spacing the record strips in the device.

Fig. 6 shows a section of one of the bearings in which the carrying elements or rolls for the strips are mounted, taken on the line 6—6 of Figure 3.

Fig. 7 is a section on line 7—7 of Figure 3; and

Fig. 8 is a section on line 8—8 of Figure 3 and Figs. 9 and 10 are top and side views, respectively of a detail of a modification.

The numeral 1 indicates a box or casing in which the essential parts of the mechanism of the marking and indicating device are housed. This casing is provided with an opening 2 in the top, at which the characters representing the desired data are exposed to view; and 3 indicates the marking member which is used as a pencil for checking what the test or examination paper presents. This element is joined by electrical conductors 4 to the circuit of the operating members in the casing 1, and current is supplied by way of a connector plug 5 joined to the device by means of a flexible cord conductor or the like and adapted to be inserted into the usual outlet terminal of a building. When the instrument is not in use the element or marker 3 can be laid in a recess 6 in the upper face of the box 1 and covered by turning down the lid thereof.

On the inside of the box are two cylindrical rollers 7 and 8. These rollers carry strips of separate tape or film or other material indicated by numerals 9, 9a, 9b, 9c and 9d. They are wound up on roller 7 and connected to the roller 8 to be transferred thereto, step by step, as required. This transfer is effected by rotating the roller 8 and drawing the strips off the roller 7. To accomplish this a solenoid 10 is mounted in the casing 1; the wiring of this solenoid being connected in series with the plug 5 and marker 3. The solenoid attracts the plunger 12 which operates a ratchet 11 rigidly connected with the roller 8. For this purpose a link 13 is pinned to one end of the plunger 12 and to an arm 14 which is movably mounted with respect to the axis of the roller 8 and upon which the pawl 15 is pivotally supported. Therefore whenever the plunger 12 is pulled back by the solenoid the ratchet 11 is turned one or more spaces through engagement thereof by pawl 15 pivoted on the arm 14.

These two rollers 7 and 8 have trunnions 17 at their ends by which they are supported in bearing members 16. At one end, such as the left end of these rollers, the bearings 16 have round openings for the trunnions 17 and at the other end, as shown in Fig. 6, the bearings have recesses 18 in the tops to receive the adjacent trunnions of the rollers, with catches or hooks 19 pivoted as at 20 to the adjacent part of the bearing, to be pushed over the adjacent trunnions and hold the rollers in place. Thus the rollers can be taken out by swinging back the retaining catches 19, lifting the adjacent end of the roller, and pulling the opposite trunnions out of the circular opening in the bearing at the opposite end of this roller.

The pawl 15 is engaged by a bent spring 34 to hold it into position to engage the ratchet 11 and a coil spring 14' attached to the arm 14 and the bottom of the box always holds the pawl in starting position and returns the pawl and plunger after the plunger 12 operates.

At the ends of the rollers 7 and 8 adjacent the solenoid 10, which is shown as being at the rear left hand corner of the casing, are bearing members 21. These members 21 have upper projecting ends 22 and they may be connected together at said ends so as to have the form of an open framework. The ends 22 are perforated at the top and said ends rotatably support short shafts 23 and 24. These shafts and the trunnions 17 of the rollers have keys and slots, so that when the shafts and the trunnions are properly engaged, said shafts may rotate the rollers 7 and 8. The shaft 23 for the roller 7 projects through one side of the bearing member 21 and carries an outside knob 26. This shaft is encircled by a coil spring 25 fastened at one end to the shaft 23 and to the bearing member 21 at the other, and this spring is wound up when the roller 7 is turned and the strip drawn off same by the other roller 8.

At the opposite end of the bearing member 21 and in the ends 22, there a similar shaft 24 detachably is keyed to the adjacent trunnion of the roller 8. On this shaft the ratchet 11 is rigidly mounted but the arm 14 is loosely mounted thereon. Therefore whenever the plunger is drawn into the solenoid, the pawl 15 engages the ratchet 11 to turn it and the roller 8 with it.

The short shaft 24 also carries opposite the ratchet 11 a hub 28 loosely mounted thereon and bearing a fixed arm 29 which projects through a slot 30 in the top of adjacent casing 1. Affixed to this hub 28 is an arc-shaped shield 27 which is curved around the axis of the shaft 24 as a center and projects under the pawl 15. When this shield is withdrawn, the full movement of the plunger will turn the ratchet through its maximum arc, and this arc can be shortened by manipulating the arm 29 and moving the shield 27 forward, so that more of its length lies between the pawl 15 and the ratchet 11. The effective stroke of the pawl 15 can thus be governed. Adjacent the slot 30 at top of the casing 1 appear the numbers 1 to 5 to indicate the positions of the arm 29 for adjusting the shield 27, so that the solenoid will operate to turn the roller 8 to a distance equal to 1, 2 and up to 5 teeth of the ratchet 11. The hub 28 has teeth 31 and to a convenient point on the adjacent bearing member is affixed a bent spring 32 to engage these teeth and retain the hub 28 and shield 27 in adjusted position.

At the opposite end of the roller 8 is a similar bearing member 21a which mounts a short shaft 33 keyed to the adjacent end of the trunnion 17 of the roller 8. On this shaft is a fixed ratchet 11a and a loose arm 14a bearing a pivoted spring pressed pawl 15a. To the arm is attached a link 13a pinned to the plunger 12a of another solenoid 10a, which is preferably disposed in the rear right hand corner of the casing 1. The teeth of the ratchet 11a are so inclined and the pawl 15a so mounted and shaped that whenever the solenoid 10a is energized the roller 8 is turned backward, preferably one space at a time. When this occurs the other pawl 15 is out of engagement with the ratchet 11, being lifted by the front end of the screen 27, thus releasing the roller 8; and the back-spacing or wind-up in the opposite di-

rection through the distance of a single character on the strips or tapes is accomplished by the spring 25, which reverses the roller 7. When not operated, a stop 37 in the bearing 21a holds the pawl 15a out of engagement with the ratchet 11a. The solenoid 10a is connected in parallel with the wires uniting the solenoid 10 to the connector plug 5. The wires which join the solenoid 10a in the circuit are led to a pair of switch contacts 42 and 43 on the bottom of the box 1; one of these, the contact 42 being movable and being operated by a plunger 44 which projects upward through a bearing 44' and an opening in the top of the box and has a button or head 45. By pressing the button the switch is closed, the solenoid 10a receives the current, and the back-spacing is thus brought about. When the circuits are open springs 14' and 14b attached to the arm 14 and link 13a respectively and the bottom of the casing return and hold the plungers and pawls to starting position.

As the roller 8 is operated to draw the strips from the roller 7 the spring 25 is wound up, as already stated, and after the pawl 15 releases the ratchet 11 the roller 8 is held against reverse rotation by a toothed wheel 38 on the short shaft 33. This wheel is engaged by a spring stop 39 on the bottom of the box 1, and this spring is set to engage the bottom of wheel 38. Connected to the spring 39 is a stem 40, extending upward through a bearing 40' on the member 21a and the top of the box and bearing an outside head 41. Hence to re-set the device after operation so as to reel back the strips from the roller 8 upon the roller 7, one has only to press the head or button 41 to release the spring 39 and free the toothed wheel 38 and the roller 8. The spring 25 now reverses the rotation of the roller 7 and reels back all of the strips to their original starting position.

The short shaft 33 also has a gear wheel 46 thereon which meshes with another gear wheel 47 on a shaft 48 in the member 21a. The gear 47 has a stop 50 projecting from one face which will move to meet a stop 49 on the bearing 21a. The ratio of the two gears 46 and 47 is such that when the roller 8 is revolved as far as the strips will permit it, the stop 50 will then engage the stop 49. See Figure 7. When the head or button 41 is pressed to release the roller 8 the gear 47 will be turned backward and the stop 50 it carries will press against the bearing 21a, having a retarding effect so as to prevent the roller 7 from being operated too rapidly by the spring 25 and making sure that the roller 8 will come to a stand-still when the re-setting is finished. The stop 50 will then meet the stop 49 on the opposite side. Thus any great stress or force on the strips or tapes 9, 9a, 9b, 9c, 9d is avoided.

The marker 3 is made up of a cylindrical casing 51 having a fixed contact 54 in one removable portion 52 connected to one terminal 53 of the supply wires 4. In line with this contact is a movable conductor stem 56 which projects through the other removable end 57 and is slidably engaged by a brush 55 connected to the other supply wire. At the outer end of the stem 56 is a graphite block 60 attached by means of a pin or screw. Other substances besides graphite can be employed. Hence whenever the marking member is used to put a mark of any kind on paper or is merely pressed far enough to make the stem 56 touch the contact 54, the circuit of the solenoid 10 will be closed and the rollers 7 and 8 will turn as far as the setting of the shield 27

allows. On the stem 56 in the casing is a collar 58, and a spring 59 around this stem, seating against an annular inside shoulder 62, holds the collar 58 against the end 57, but allows inward motion of the stem.

The strips on the rollers bear grading data by which the score of the pupil taking the test is determined. The data in question may be varied and, for the sake of example, the strip 9a will present numbers on its upper face from 100 down to zero. The adjacent strip 9 will carry numbers from zero to 100. Thus the tape 9 can be actuated to add the desired units and the tape 9a can be actuated to subtract the desired units. Either tape 9 or 9a or both tapes may carry numbers that are multiples and grow larger thereby, or numbers that are divided by desired units.

The other tapes or strips may carry thereon data corresponding to each combination of indications given by the first two tapes or tapes 9 and 9a, and when the scanning of each paper is completed the strips of tape or film will show the data necessary to give the complete results and grades which the test discloses.

For example, a teacher may be marking a paper with twenty questions thereon, so that each question counts for 5 in grading the paper. In reviewing the paper the member 3 may be so held that when the correct answer is found, a check mark can be made with the graphite crayon 60 without closing the circuit in the member 3 and thus not actuating the instrument at all. If, however, the answer is found to be wrong, so that 5 must be taken off, the reviewer manipulates the arm 29 to set the shield 27 so that when pressure is exerted on the crayon 60 the electrical operating circuit will be closed and the roller 7 and 8 will be operated to turn through a distance equal to five teeth of the ratchet wheel 11. This will move the tapes so that the first two for example, will bring the numbers 5 and 95 in position to be seen in the opening 2. If 3 is to be deducted the arm 29 will be manipulated so that the ratchet is moved through a distance of only three of the teeth. Thus the whole paper can be graded and when the examination is finished the total figure deducted will appear on the tape 9 and the final grade mark will be shown on the tape 9a. Similar data indicating the student's full rating in connection with the paper will appear on the tapes 9b, 9c and 9d. The subject matter on the last named tapes will of course be properly related to the numbers shown on the tapes 9 and 9a.

In Figures 9 and 10, the solenoid 10 is shown as joined by a link 13' to a lever 13a, pivoted at 13b to the casing at one end and united by a short link 13c at the other end to the pawl-carrying element 14. The arm 29' adjusts the stroke of the pawl, that is drawn towards the ratchet 11 by a spring 34'. The arm 29' adjusts the shield 27 which is steadied by a spring 32' engaging teeth 31 on the member 28' carrying the screen 27 and arm 29' and mounted loosely on shaft 24.

From the foregoing description it will be seen that I have devised a very simple and reliable instrument for marking and grading test papers. The device is not expensive to produce and after the operator has completed looking over each paper the whole instrument can be re-set for further use. It can be back-spaced at any time to the required extent and the forward movement of the rollers 7 and 8 can be increased or decreased, as the answer to any particular question or part of the paper necessitates.

The design and construction of the marking element 3 is a special feature of the entire combination because it causes actuation of the rollers every time pressure is put upon the end of the marker to close the circuit of the solenoid 10. The actuation of the rollers is thus independent of the amount of pressure on the marking element or the length of time during which said element is kept under pressure or held against the paper by the user.

Having described my invention, what I believe to be new is:

1. An indicating instrument comprising a casing having therein a roller, a spring to be put under tension as said roller turns, a second roller, strips to be attached to the rollers to be unwound from the first roller and taken up by the second roller, a solenoid, a pivoted arm mounted concentric with the second roller, a ratchet wheel in fixed relation to the second roller, a pawl on said arm to engage the ratchet wheel, a plunger in said solenoid connected to said arm, a pivoted curved member concentric with the second roller normally holding the pawl out of engagement with said ratchet to shorten or lengthen the extent of actuation of the said second roller by the solenoid, an arm attached to said curved member, the casing having an opening through which the last-named arm projects, and an opening exposing said strips, a movable member containing a switch in circuit with the solenoid to close the circuit, and means on said movable member operative to close the switch and to mark said strips.
2. An indicating instrument comprising a casing having therein a roller, a spring to be put under tension as said roller turns, a second roller, strips attached to said rollers, the casing having an opening exposing said strips, means for intermittently rotating the second roller to draw the strips thereon from the first roller, a toothed wheel connected fast to the first roller, a stop engaging said wheel, a stem projecting to the outside of the casing to release the stop, a ratchet wheel in fixed relation to the second roller, a pivoted arm mounted concentric with the second roller, a pawl on the arm to engage the ratchet and rotate said roller in reverse, a fixed stop in the casing normally holding said pawl inoperative, a solenoid having a plunger connected to said arm, switch parts in the casing in circuit with the solenoid, a plunger extending outside the casing to operate the switch, a fixed stop in the casing and a wheel geared to the second roller having a stop to engage the fixed stop at both ends of the rotation of the first roller.
